US0D1054987S

(12) **United States Design Patent** (10) **Patent No.:** **US D1,054,987 S**
(45) **Date of Patent:** **** Dec. 24, 2024**

(54) **BATTERY CELL HOLDER**

(71) Applicant: **Samsung SDI Co., Ltd.**, Yongin-si (KR)

(72) Inventors: **Seokbin Yoon**, Yongin-si (KR); **Deayon Moon**, Yongin-si (KR); **Kwangsoo Bae**, Yongin-si (KR)

(73) Assignee: **Samsung SDI Co., Ltd.**, Yongin-si (KR)

(**) Term: **15 Years**

(21) Appl. No.: **29/790,781**

(22) Filed: **Dec. 14, 2021**

(30) **Foreign Application Priority Data**

Jun. 17, 2021 (KR) 30-2021-0028827

(51) **LOC (14) Cl.** **13-02**

(57) **CLAIM**

The ornamental design for a battery cell holder, as shown and described.

DESCRIPTION

FIG. 1 is a front perspective view of the battery cell holder;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is an enlarged view of area 8 in FIG. 1.

The dash-dot broken line is for the purpose of defining the enlarged view and forms no part of the claimed design. The dash broken lines indicates portions of the battery cell holder that form no part of the claimed design.

1 Claim, 8 Drawing Sheets
